UNITED STATES PATENT OFFICE

JOHN FORBES, OF HALIFAX, NOVA SCOTIA, CANADA.

SEAL-LOCK FOR CAR-DOORS.

SPECIFICATION forming part of Letters Patent No. 314,009, dated March 17, 1885.

Application filed June 9, 1884. (Model.)

To all whom it may concern:

Be it known that I, JOHN FORBES, of Halifax, in the Province of Nova Scotia, Canada, have invented a new and useful Improvement 5 in Seal-Locks for Car-Doors, of which the following is a full, clear, and exact description.

This invention has reference to an improvement on the seal-lock patented to myself and H. M. Williston on the 6th day of March, 10 1883, in Letters Patent numbered 273,267. As the locking mechanism is the same in the lock now improved as that shown in the lock of said Letters Patent, such locking mechanism will not be here described, nor shown in 15 detail in the drawings, except so far as it will be necessary to explain the improvement I have made on the seal-lock.

The object of my invention is to prevent the paper seal being withdrawn in any event, 20 except by defacement, and thus not allow of its use thereafter as a perfect seal.

In the drawings, Figure 1 is a view of a freight-car door with the seal-lock attached thereto. Fig. 2 is a plan view of the seal-lock, showing the paper seal in position and the device locked. Fig. 3 is a similar view of the lock, but showing the slide pushed up in order to get at the unlocking-pin, and the consequent defacement of the paper seal. 25 Fig. 4 is a vertical longitudinal central section taken in the line $x-x$ of Fig. 3, the plate and locking-pin shown as thrown back in order to release the car-door staple and to insert a fresh paper seal. Fig. 5 is a vertical longitudinal section of the seal-lock. Fig. 6 is a 35 view of the seal-lock from the under side.

a is the seal-lock frame or casing. b is a plate hinged to this frame, carrying the articulated locking-bolt c . 40 d is a bent rod, the bent end resting in a recess in order to be covered or confined therein by sealing with the superimposed paper seal. The lock cannot be opened without breaking or the removing of such paper seal and turning the bent end d of the rod sufficient to bring its lower end into operation with locking mechanism in the lower portion of the case, and thereby release the bolt c , which locking mechanism and operation there-

of, in combination with said rod d , will all be 50 found fully described in said Patent No. 273,267, and need not be here described.

e is a slide-plate passing between the face of the lock and the hinge of the plate b . This plate has an opening in it, so that the paper 55 seal is visible over the bent rod d , and slides in grooves made in the side walls of the casing.

f f are narrow strips or arms of spring steel, one on each side of the slide-plate e , attached thereto about half-way of its length, and containing on their lower sides pins g g , &c. These pins, when the said strips of steel are pressed down, pass into holes or openings h h , &c., made in the slide e , so that 60 when a seal is placed between these strips of steel and the slide locked by the closing of the plate b , as seen in Fig. 2, the said pins g g will pass through the sides of the seal and into such holes h h , and securely hold the seal 65 over the bent rod, so that it cannot be removed therefrom by picking and consequent defacement or by the opening of the lock, except by the pushing up of the slide-plate e 70 and the complete defacement of the seal, as 75 seen in Fig. 3.

The operation of the improved portions of the seal-lock is as follows: The plate b and the locking-bolt c are thrown back, as seen in Fig. 4. A seal is then inserted between the 80 pins g g , &c., of the spring-arms f f and the holes h h , &c., in the slide e . The slide is then pulled down over the bent rod d —that is, into the position shown in Fig. 2—and the plate b and locking-bolt c thrown forward, 85 thus locking down the paper seal securely.

In order to get at the bent rod d to open the lock, and thus release the plate b and locking-bolt c , the slide-plate e must be pushed forward, which, while such movement exposes to view the end of the bent rod d it at the same time causes the said plate to ruckle up and destroy the paper seal. This position of the slide-plate e and consequent destruction of the seal is seen in Fig. 3. 95

I claim—

1. In a seal-lock, the combination of a slide-plate, e , with spring-arms f f , said arms

provided with pins *g g*, adapted to pass into openings *h h* made in such slide-plate *e*, and a bolt-locking mechanism, substantially as and for the purposes described.

5 2. In a seal-lock, the combination of a slide-plate, *e*, with spring-arms *ff*, said arms provided with pins *g g*, adapted to pass into open-

ings *h h* made in the slide-plate *e*, plate *b*, bolt *c*, and rod *d*, substantially as and for the purposes described.

JOHN FORBES.
